Primary Examiner — R. Johnson(74) *Attorney, Agent, or Firm* — Neal, Gerber & Eisenberg LLP(57) **CLAIM**

The ornamental design for a shoulder rest for a violin or viola as shown and described.

DESCRIPTION

FIG. 1 is a top perspective view of a shoulder rest for a violin or viola showing our new design.

FIG. 2 is a left side view of the shoulder rest of FIG. 1.

FIG. 3 is a bottom perspective view of the shoulder rest of FIG. 1.

FIG. 4 is a top view of the shoulder rest of FIG. 1.

FIG. 5 is a front view of the shoulder rest of FIG. 1.

FIG. 6 is a bottom view of the shoulder rest of FIG. 1.

FIG. 7 is another top perspective view of the shoulder rest of FIG. 1.

FIG. 8 is a right side view of the shoulder rest of FIG. 1; and, FIG. 9 is another bottom perspective view of the shoulder rest of FIG. 1.

(Continued)

The broken lines represent portions of the shoulder rest for a violin or viola that form no part of the claimed design.

1 Claim, 9 Drawing Sheets
